BEVERAGE TRAY FOR VEHICLES

William F. Bealer, 118-0 Via Estrada,
Laguna Hills, Calif. 92653

Filed Aug. 16, 1971, Ser. No. 171,836

Term of patent 14 years

Int. Cl. D7—99

U.S. Cl. D87—1

FIG. 1 is a top front perspective view of a beverage tray for vehicles showing my new design;

FIG. 2 is a top plan view thereof;

FIG. 3 is a bottom plan view thereof;

FIG. 4 is a front elevational view thereof;

FIG. 5 is a right side elevational view of FIG. 1; and

FIG. 6 is a left side elevational view of FIG. 1.

I claim:

The ornamental design for a beverage tray for vehicles, substantially as shown.
